CONTAINER

Harold G. Carsley, Waukegan, Ill., assignor to
 Cyclone Fence Company, a corporation of New
 Jersey

Application January 3, 1939, Serial No. 249,679

6 Claims. (Cl. 229—5.7)

This invention relates to containers, and particularly to those made of paper or cardboard and including an improved closure means characterized by a member serving the dual function of a locking means and a strengthening means. While not limited thereto, the present invention is well suited for incorporation in nail kegs, the main body portions of which are made of piles of paper with a layer of reenforcing wire fabric associated therewith. Various other detail features and advantages of the invention will be apparent from the following disclosure, when read in connection with the accompanying drawing, in which:

15 Figure 1 is a side elevation of a nail keg embodying the invention;

Figure 2 is a plan thereof;

Figure 3 is an enlarged vertical section on line III—III of Figure 2;

20 Figure 4 is a plan of Figure 3 with portions broken away in the interests of clarity; and

Figure 5 is a detail horizontal section on line V—V of Figure 3.

Referring in detail to the drawing, in the embodiment of the invention illustrated the numeral 10 represents generally the main body portion of a cylindrical nail keg. This body portion comprises inner and outer plies 12 and 14 of paper, cardboard or the like, between which there is interposed a reenforcement of wire fabric 16. This reenforcement may be in the nature of commercially obtainable metallic screen cloth composed of interengaging warp and weft strands woven together or otherwise interconnected.

35 The woven fabric is constructed of metal wire of very light gage, comparable to that used for ordinary window screening. It is bonded or intimately secured to the plies 12 and 14 by the use of a suitable adhesive, such as known types of asphaltic, resinous or hydrocarbonaceous materials. The overall or multi-ply thickness of the wall 10 is of the order of approximately $\frac{1}{8}$ of an inch. With such thin material it is important to provide means to resist collapse, particularly

45 at the top and bottom, where the heads or end closures are secured. For this reason I deem it important to provide an end assembly which serves the double function of securing the head in place at the end of the container and also reenforcing the same. Containers such as nail kegs and the like preferably are of inexpensive construction. To this end I have devised the improved end closure structure herein shown and claimed which is peculiarly well suited for use in

55 combination with a container whose main body

is made of paper, cardboard, or similar thin light material possessed of relatively low inherent resistance to collapse.

The improved end closure assembly may be used at both top and bottom of the container. Such end assemblies are indicated generally at the base by 18 and at the top by 20. It is not essential, however, that the construction be the same at both top and bottom.

More specifically, the end assembly embodying characteristics of the present invention involves the use of an outer annular strap 22 and an inner closure or head receiving rim 24. The outer annular strap is a plain strap, the ends of which are overlapped, as indicated in Figure 5, and spot welded together, as indicated at 26. The ends of the inner closure rim 24 are similarly overlapped and spot welded together, as indicated at 28. The strap 22, the main body 10 and the rim 24 are firmly secured to one another by suitable means, such as the staples 25, whose inner extremities are bent over or clinched, as clearly shown in Figure 5.

The inner rim 24 is provided intermediate its ends with a pair of opposed, inwardly extending flange portions 30 and 32 united by the bent portions 34. The flange portion 32 forms an annular shoulder upon which is seated the closure or head 36. This head is preferably, although not necessarily, made of plywood or the like of approximately $\frac{1}{4}$ inch in thickness.

At the outer extremity of the rim 24 there is an outwardly extended portion 38 of substantially U-shape forming an annular seat 40 which coacts with a ring 42 which, in combination with the outer annular strap 22, the inner head receiving rim 24 and the head 36 serves the double function of a reenforcement and locking means for releasably holding the head 36 firmly seated on the annular shoulder 32. In order that the ring 42 shall contribute to this double function, it is important that it possess two main characteristics; first, it shall be of a thickness materially greater than that of the thin sheet metal of which the strap 22 and the rim 24 are constructed; second, it shall be much wider than its thickness. In the embodiment illustrated, the strap and rim are made of flat sheet steel approximately $\frac{1}{8}$ of an inch in thickness, whereas the ring 42 is approximately $\frac{1}{8}$ of an inch in thickness and $\frac{1}{2}$ inch in width, as measured radially. The ring is preferably made of iron or steel and possesses a certain amount of inherent resiliency. Such a ring, which in cooperation with other parts, performs the double func-

tion of reenforcing the end of the container as well as that of locking the head in place, may be referred to briefly as a reenforcing locking ring. The ring is preferably split and the ends thereof notched, as indicated at 44 and 46, so that the tongue portions 48 and 50 thereof overlap to normally lock the ring in an expanded condition within the annular seat 40. The inner surface of the ring is substantially flat, as indicated at 52, and the outer face of the ring is convex, as indicated at 54. This sectional contour provides a flat seating surface for effective coaction with the flat upper surface of the head 36, and the rounded outer surface provides sufficient taper to facilitate engagement and disengagement with the grooved seat 40.

The relationship of the overlapping tongues 48 and 50 and their relation to the notched portions of the ring provide a readily detachable split joint. Once the parts are assembled the keg can be readily opened merely by the insertion of a suitable prying tool in the space 56 between the opposed tongues. Upon prying the tongues apart the inherent resiliency of the locking ring 42 will cause one end of the ring to spring inwardly and thus facilitate the prying out of the remaining portion of the ring, it being understood that the remaining portion will be wedgingly engaged with the annular seat or groove 40 of the rim 24. In the described construction it will be apparent that when the locking ring 42 is in its normal operative position, illustrated in Figures 3 and 4, due to the curved upper surface thereof, its peripheral portion will wedgingly engage the outer flange of the U-shaped seat 40. Because of the interlocking of the ends of the ring and the engagement of the ring as a whole with the annular seat 40 and the fact that the ring is of relatively thick metal as compared to the thickness of the strap 22 and the rim 24, it will be apparent that the ring 42 serves to retain the head 36 in position, and also to stiffen and rigidify the entire end closure assembly. This is desirable as all other parts, with the exception of the plywood head, are made of very thin sheet material of relatively low inherent strength and low resistance to collapse. It is deemed preferable, in order that the ring may cooperate with the other parts to serve the double function, that it be of a cross sectional contour other than circular. This is because a ring of circular cross section of sufficient strength to adequately resist collapse would be so large that an outer portion 38 of undesirable size would be required and such an enlarged round ring would not have the desirable flat surface to properly seat against the flat face of the head. The relatively wide, flat, thick ring of the contour shown and described therefore meets the essential requirements in a manner in which they would not be met by a ring of circular cross section. The outwardly extended portion of the rim 38 which forms the annular seat for receiving the ring 42 also functions to protect the fabric of the keg when the same is rolled on the floor, it being apparent from the drawing that the overhanging of the rim is sufficient to space the keg wall 14 away from the floor when the keg is being rolled on the annular rim 38. While I have described quite specifically the embodiment of the invention herein illustrated, it is to be understood that I am not limited thereto, since various modifications and substitutions of equivalents may be made without departure

from the invention as defined in the appended claims.

I claim:

1. A container of the character described comprising a body portion formed of non-metallic material having at one end thereof an outer annular strap and an inner head retaining rim of relatively thin metal engaging the outer and inner surfaces respectively thereof, inwardly projecting head supporting means carried by said rim; a head seated thereon, said rim having an inwardly opening annular grooved portion and a detachable reenforcing locking ring seated in the grooved portion and overlapping said head, the thickness of the ring being greater than that of said rim.

2. A container of the character described comprising a body portion formed of reinforced fibrous material having secured at one end thereof an outer annular strap and an inner head retaining rim of relatively thin metal, an inwardly projecting annular shoulder formed on said rim, a head seated thereon, said rim having an outwardly extended substantially U-shaped portion covering the upper edge of said fibrous body and forming an inwardly opening annular seat, a metallic split ring of materially greater thickness than the metal of said rim and effective in cooperation with the rim to reinforce the end structure of the container and releasably lock the head within the confines of the rim.

3. A container of the character described comprising a substantially circular main body formed of inner and outer fibrous sheets with a reenforcing metallic fabric interposed therebetween, an outer strap encircling an end of said body, an inner rim of thin sheet metal including a pair of inwardly projecting annular flanges connected with one another at their inner extremities forming a head support, a head seated on the support thus formed, said rim having an outwardly projecting substantially U-shaped portion overlapping the extremity of the upper head of said fibrous body and forming an inwardly opening annular groove, a detachable reenforcing metallic ring of non-circular cross section whose thickness is materially greater than the thickness of said rim and whose width is materially greater than its thickness so that it performs the double function of impositively locking the head in place and reinforcing the end of the container.

4. The container of claim 3, wherein said ring is split to form overlapping tongue portions to facilitate the removal thereof.

5. A keg including a main circular wall comprising inner and outer strata of paper with an intermediate reenforcement of wire fabric interposed between and adhesively united thereto, a thin metal strap encircling an end thereof, an inner rim of thin metal having an inwardly extending head supporting shoulder and having an inwardly opening substantially U-shaped annular seat at the extremity thereof overlying the end of said circular wall, a head within the confines of said rim, a reenforcing locking ring whose thickness is greater than that of said rim and whose width is materially greater than its thickness, having an outer portion engaging said seat and an inner portion overlapping said head, said ring being split transversely to facilitate removal thereof.

6. The keg as defined in claim 5 wherein the strap and rim are secured to said main body by securing means piercing the latter.

HAROLD G. CARSLEY.
